UNITED STATES PATENT OFFICE

GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

FLUID PRESSURE TOOL

Application filed April 6, 1929. Serial No. 353,208.

This invention relates to percussive tools of the fluid pressure type. More particularly it concerns the automatic control and distribution of the motive fluid to the percussive 5 motor and the valve mechanism and porting arrangement.

One object of the invention is to provide a motor for tools of the described type having a valve structure which is simple and compact. Another object is to make the fluid and shifting ports between the valve and piston chambers short and direct. Another object is to make the valve quick acting in its reversals and the entire tool economical in the use 15 of motive fluid. Still other objects will be apparent from the detailed description which follows.

In order to illustrate the invention, one concrete embodiment thereof is shown in the 20 accompanying drawings, in which:

Fig. 1 is a longitudinal sectional view through a fluid pressure rock drill; and

Fig. 2 is a sectional view similar to Fig. 1 but showing the piston and valve in different 25 positions.

In the preferred form of the invention shown in the accompanying drawings, the percussive tool comprises a cylinder 3 provided with a piston chamber within which 30 reciprocates a hammer piston 4 having a fluted extension 4a guided by a bushing 5 in the forward end of the cylinder and having cooperating sliding engagement with the fluted portion of a chuck 6 mounted for rotation in a front head 7. A hollow drill steel 8 supported in chuck 6 receives the blows of piston 4. Cylinder 3 has a main exhaust port 3a through the wall thereof so arranged as to be overrun by piston 4 in both directions of 40 movement.

The movement of piston 4 is controlled by an automatically operated tubular valve 9 disposed immediately adjacent the piston chamber in a valve case formed by bushing 45 members 10 and 11. The motive fluid enters the bore 10a of bushing 10 directly into the bore of hollow valve 9. The ends of the valve control the admission of motive fluid from the inlet to end chambers 12 and 13, depending 50 upon the position of the valve, which end

chambers communicate with the opposite ends of the piston chamber by short and direct ports 12a and 13a respectively. Valve 9 has a radially extending flange 9a providing opposed shift areas 14 and 15. These areas 55 form movable walls for chambers 16 and 17 respectively, which are continuously supplied with motive fluid in limited amount from the central bore of the valve by ports 9b through the valve itself. Chambers 16 and 17 communicate directly with the piston chamber on opposite sides of main exhaust 3a through ports 16a and 17a, respectively, under control 60 of piston 4. Intermediate chambers 16 and 12 on one side of flange 9a, and intermediate 65 chambers 17 and 13 on the other side, are vent chambers 18 and 19 respectively, which are alternately placed in communication with end chambers 12 and 13 by annular grooves 9c on the valve. 70

With the tool in operation, and the parts in the position shown in Fig. 1, motive fluid entering inlet 10a passes into chamber 12 and through passage 12a to the rear end of the piston chamber, driving piston 4 forwardly. The forward end of the chamber is open to exhaust through main exhaust port 3a, through an auxiliary exhaust formed by the projection of the flutes on piston 4a into the piston chamber thereby establishing communication with the hollow bore of the drill steel, and by the valve controlled vent comprising port 13a, chamber 13, valve grooves 9c, and vent chamber 19. Port 17a, being uncovered, vents the motive fluid continually 85 passing to chamber 17 but that passing to chamber 16 is effective against area 14 to hold the valve in its forward position since port 16a is sealed by the piston. Of the two other pairs of opposing areas on the valve, the areas 90 formed by the ends of the valve are in balance since both are in communication with the motive fluid supply, but the sealing projection or flange between chambers 12 and 18 assists in holding the valve in the forward 95 direction since the corresponding projection at the other end of the valve is disposed in a chamber open to exhaust.

As the piston advances it first covers the main exhaust 3a and then port 17a, where- 100

upon pressure builds up in chamber 17 against area 15 to balance area 14. Shortly thereafter piston 4 overruns main exhaust 3a as it delivers its blow upon drill steel 8. The consequent drop in pressure in the rear end of the piston chamber, which is now in communication with flange chamber 16 through the uncovering of port 16a, causes a drop in pressure in chamber 16, resulting in a prompt shifting of the valve to the position shown in Fig. 2 by reason of the predominating pressure in chamber 17 effective against shift area 15. With motive fluid now passing through the bore of valve 9 into end chamber 13 and thence through port 13a into the forward end of the piston chamber to drive the piston rearwardly, vent chamber 19 is closed off from end chamber 13 while vent chamber 18 is in communication with the opposite end chamber 12 through groove 9c in the valve thereby establishing an auxiliary exhaust for the rear end of the piston chamber. The valve is held in its rearward position through the pressure on shift area 15 and upon the sealing projection or flange between end chamber 13 and vent chamber 19. As the piston moves rearwardly it closes main exhaust 3a and shortly thereafter the flutes on piston extension 4a project into the forward piston chamber causing a slight reduction in the pressure as a portion of the motive fluid passes along the flutes and down the hollow bore of the drill steel to blow the cuttings out of the hole. This drop in pressure is not sufficient to cause any shifting of the valve and may be omitted entirely, if hole cleaning on the back stroke is not desired, by arranging the flutes so that they do not project into the piston chamber until piston 4 has opened, or is about to open, main exhaust 3a. With the uncovering of main exhaust 3a there is a pressure drop in flange chamber 17, whereupon the predominating pressure against the opposing shift area 14 throws the valve quickly to forward position, thus completing the cycle.

While the invention is herein disclosed in what is now considered to be a preferred form, it is to be understood that the invention is not limited to the specific details thereof, but covers all changes, modifications, and adaptations within the scope of the appended claims.

I claim as my invention:

1. A fluid pressure tool comprising a cylinder providing a piston chamber having an exhaust port, a piston reciprocable in said chamber and arranged to overrun said port, said cylinder providing a valve case adjacent said piston chamber, a tubular valve movable in said case in timed relation with said piston, said case providing chambers at each end of the valve with ports opening into the ends of said piston chamber, the ends of said valve controlling the supply of motive fluid to said

end chambers, the bore of said valve serving as a conduit for the motive fluid and the end areas of said valve being in open communication with said conduit in all positions of said valve, and a radial flange on said valve intermediate the ends thereof providing opposing shift areas, said case providing chambers on either side of said flange having ports opening into said piston chamber on opposite sides of said main exhaust port and under control of said piston, said valve having restricted ports therethrough on opposite sides of said flange to supply motive fluid continuously in limited amount to said flange chambers, said case providing vent chambers on either side of said flange between said flange chambers and said end chambers, and means establishing a connection between each of said end chambers and the adjacent vent chamber when said valve is in position to shut off the motive fluid supply to the said end chamber.

2. A fluid pressure tool comprising a cylinder providing a piston chamber having an exhaust port, a piston reciprocable in said chamber and arranged to overrun said port, said cylinder providing a valve case adjacent said piston chamber, a tubular valve movable in said case in timed relation with said piston, said case providing chambers at each end of the valve with ports opening into the ends of said piston chamber, the ends of said valve controlling the supply of motive fluid to said end chambers, the bore of said valve serving as a conduit for the motive fluid and the end areas of said valve being in open communication with said conduit in all positions of said valve, and a radial flange on said valve intermediate the ends thereof providing opposing shift areas, said case providing chambers on either side of said flange having ports opening into said piston chamber on opposite sides of said main exhaust port and under control of said piston, said valve having restricted ports therethrough on opposite sides of said flange to supply motive fluid continuously in limited amount to said flange chambers, said case providing vent chambers on either side of said flange between said flange chambers and said end chambers, and means establishing a connection between each of said end chambers and the adjacent vent chamber when said valve is in position to shut off the motive fluid supply to the said end chamber.

Signed by me at Detroit, in the county of Wayne, and State of Michigan this 23 day of March, 1929.

GUSTAVE M. NELL.
